UNITED STATES PATENT OFFICE.

RICHARD W. WOOD, OF BEND, CALIFORNIA.

CARD-INDEX CONTAINER.

Application filed November 23, 1925. Serial No. 70,772.

My invention relates to drawers, boxes or any containers holding index cards, loose leaf sheets or folders, and constructed so as to adjust one card or sheet above the other.

5 Among the salient objects of the invention are to provide a container having a crimped or corrugated plate on bottom and other construction, whereby the portion of the cards or loose leaves of any kind may be raised 10 one above the other automatically, so that any markings on the top edge of cards can readily be seen at a glance by reason of being raised one above the other, which are placed in that position automatically by the 15 crimped plate on the bottom of the drawers or containers.

When the cards or leaves are placed on these crimped plates they automatically place the cards one above the other according to the size of the crimp in the plates, so that when placed on these crimped plates the cards are self-adjusting as well as automatically raised one above the other.

20 These containers are particularly desirable to be used in combination with vertical filing where indexing of the cards or leaves is desired to be extended beyond the main guides, and where markings are placed on the top edges of cards or leaves.

25 To the above ends the invention consists in the matters hereinafter set forth and will be readily understood from the following description, reference being had to the accompanying sheets of drawings in which

30 Fig. 1 is a front face view showing a container holding a crimped plate, a main guide, sub guide, and cards, with markings on the top edge of the cards. 1 designates cards one above the other which are placed 35 on the crimped plates as also the guides. 2 shows the sub guide; 3 an indicator opposite the letter J, and 4 the main guide, and 5 the crimped plate at bottom while 6 indicates the markings which as shown are elongated in form and may be applied to 40 the cards with a rubber stamp or by a pen.

45 Fig. 2 shows end view of container with cards and guides and crimped plates at bottom. 1 shows the top of cards; 2 shows the top of sub-guides; 4 the main guide, and 5 the crimped plate, at bottom.

50 Fig. 3 is a top view of the crimped plate. 5 shows the crimps or grooves where cards automatically adjust themselves one above 55 the other.

Fig. 4 is end view of the crimped plate.

The sub index guides have the letters of the alphabet on their top edge and the desired card is found by selecting the required letter of the name on the card.

60 For example, if SAN are the letters on the main guide and the required card has the name San Francisco, the card is found by selecting the marking 6 on card opposite the letter F on the sub-guide which is the fourth 65 letter of the name, San Francisco. The indicators 3 may also be used for the same purpose, but the marking of the cards is less expensive and of course the indicators 3 may be lost but such a casualty could not happen 70 when the markings are used. The raising of cards one above the other in the manner described not only raises the cards showing the markings 6 and letters plainly and quickly by reason of their position on the 75 crimped plates, but they are more easily and quickly handled.

Letters, alphabetically arranged, are printed at the top of each card so that the edge above any desired letter may be blackened with accuracy. A person is thus enabled to tell by a mere glance at the top of the marked cards in the cabinet where to find a portion of a name beginning with a certain letter. It is to be understood that the 80 initial letter or letters of a name are to be found upon the main guide 4, and that the first letter of the second syllable or portion of the name sought is indicated by the position of the edge marking 3 of the card in 85 reference to the sub guide 2.

I do not claim any particular system of lettering or numbering the index cards, since the method I use is essentially that of the expired patent of Denlinger, Feb. 11, 1908, 95 but

I claim:

1. A card index of the character described comprising a container, corrugated means arranged in the bottom of said container, 100 cards adapted to be supported on said means and including cards having all of the letters of the alphabet arranged across the top to provide sub-guides adapted to be supported upon the raised portions of the corrugated means for displaying the letters, main guides having a portion of words thereon and disposed above all the cards an indicator on other cards to cooperate with the letters to indicate the remaining portion 105 of the words and the cards carrying the indicators being adapted to be also sup-

ported on the raised portions of the corrugated means whereby they can be readily seen.

2. A card index of the character described comprising a container, cards adapted to be arranged in said container, some of said cards being provided with the letters of the alphabet arranged across the top thereof to provide sub-guides, main guides having a portion of words thereon and arranged to

be disposed above the cards, elongated markings on other cards to cooperate with the sub-guides to indicate the remaining portion of the words and a corrugated plate arranged in the bottom of the container to make the letters of the alphabet and the markings visible above the remaining cards. ¹⁵

In testimony whereof I affix my signature.

RICHARD WM. WOOD.
